UNITED STATES PATENT OFFICE

WILLY MESSERSCHMITT, OF AUGSBURG, GERMANY

FLYING MACHINE

Application filed February 18, 1930, Serial No. 429,804, and in Germany February 23, 1929.

My invention relates to flying machines and more particularly to the connection of the wings with the fuselage.

It is an object of my invention to reduce the number of fittings required for this connection. In the flying machines as hitherto designed four or more fittings are provided which require very exact workmanship and involve a considerable increase in weight.

10 In order to overcome these drawbacks I provide fittings at three points only, two of them being arranged at the end of the front spar, the third at some distance to the rear. The two fittings in front absorb the bending stresses while the third fitting at the rear absorbs the fore- and aft-forces and the torsional stresses.

My invention may be adapted to wings with a front and rear spar, and to wings with 20 a front spar only. In the latter case a bracing which will be referred to as the "auxiliary spar" is provided, extending between the front spar and the rear fitting.

25 In the drawings affixed to this specification and forming part thereof, flying machines having the arrangement of fittings embodying my invention are illustrated diagrammatically by way of example.

In the drawings

30 Fig. 1 is a diagrammatic elevation of a flying machine with wings having a front and a rear spar,

Fig. 2 is a plan view of one of the wings and the adjacent part of the fuselage,

35 Fig. 3 is a diagrammatic elevation of a machine with wings having a front spar and an auxiliary spar,

Fig. 4 is a plan view of one of the wings and the adjacent part of the fuselage,

40 Fig. 5 shows the parts illustrated in Fig. 4 drawn to a larger scale,

Fig. 6 is a section on the line VI—VI in Fig. 5,

45 Fig. 7 is a section on the line VII—VII in Fig. 5 and

Fig. 8 is a section on the line VIII—VIII of Fig. 5.

50 Referring to the drawings, 1 is the fuselage, 2 is one of the wings, 3 is the front

spar with the fittings 7 and 8, and 4 is the rear spar.

Referring more particularly to Fig. 1, the wing 2 is equipped with a front spar 3 and a rear spar 4. The front spar 3 is provided with the usual upper and lower flanges 5 and 6, with the fitting 7 at the top, and the fitting 8 at the bottom, Fig. 7, and corresponding fittings 9 and 10 are provided on a frame or bulkhead 11 of the fuselage 1. The rear spar 4 is provided with a single fitting 12.

Figs. 3, 5 and 8 show a wing having only the front spar 3. Here the third fitting 12 is attached to an auxiliary spar 13 which extends from the front spar to the fitting and is built-up from two struts, each extending across a bay between two of the wing ribs 14. As it is desirable that the auxiliary spar 13 should not be too stiff, it is connected to the front spar 3 at the third rib 14. As it is also desirable that the connection of the auxiliary spar 13 with the second rib 14 should be in the axis of the wing, it is kinked so that its point of intersection with the second rib lies in the plane of the axis 15, as shown in Figs. 4 and 5. Obviously the auxiliary spar may be so arranged as to extend through any number of bays and may be designed without any kink.

Fig. 8 shows the bracing of the auxiliary spar 13, 16 and 17 being diagonal wires which are attached to the fitting 12 at 18 and 19. Instead of braces a built-up girder similar to the front spar 3 might be provided to form the auxiliary spar. This spar may even be built-up altogether from diagonal wires such as 16 and 17, without any girder parts.

The fittings 9 and 10 at the frame or bulkhead 11 are secured to transverse struts 20 and 21 of the frame or bulkhead 11 by rivets 22. The fittings 7 and 8 may be connected with the respective flanges by rivets 23 or by screws. 24 is the inner end wall of the wing and 25 is the cover of the fuselage.

I wish it to be understood that I do not desire to be limited to the exact details of construction shown and described for obvious modifications will occur to a person skilled in the art.

100 In the claims affixed to this specification

no selection of any particular modification of the invention is intended to the exclusion of other modifications thereof and the right to subsequently make claim to any modification 5 not covered by these claims is expressly reserved.

I claim:

1. A flying machine having a fuselage, a pair of cantilever wings, a front spar in each wing, two fittings for securing said wing to said fuselage spaced apart on said front spar, an auxiliary spar connected with said front spar, and a third fitting at said auxiliary spar.
- 10 2. A flying machine having a fuselage, a pair of cantilever wings, a front spar in each wing, two fittings for securing said wing to said fuselage spaced apart on said front spar, an auxiliary spar connected with said front spar and arranged at an angle to the axis 15 of said wing, and a third fitting at said auxiliary spar.
- 20 3. A flying machine having a fuselage, a pair of cantilever wings, a front spar in each wing, two fittings for securing said wing to said fuselage spaced apart on said front spar, a kinked auxiliary spar connected with said front spar, and a fitting at said auxiliary 25 spar.
- 30 4. A flying machine having a fuselage, a pair of cantilever wings, a front spar in each wing, two fittings for securing said wing to said fuselage spaced apart on said front spar, an auxiliary spar consisting of bracing means 35 connected with said front spar, and a third fitting at said auxiliary spar.

In testimony whereof I affix my signature.
WILLY MESSERSCHMITT.
